DESIGN FOR A BROOCH

Louis Silverfield, San Francisco, Calif.

Application September 7, 1940, Serial No. 94,841

Term of patent 7 years

To all whom it may concern:

Be it known that I, Louis Silverfield, a citizen of the United States of America, residing at San Francisco, in the county of San Francisco and State of California, have invented a new, original, and ornamental Design for a Brooch, of which the following is a specification, reference being had to the accompanying drawing, forming a part thereof:

Fig. 1 is a perspective view of a brooch, showing my new design;

Fig. 2 is a rear elevation thereof; and
Fig. 3 is a top plan view thereof.

I claim:

The ornamental design for a brooch, substantially as shown.

LOUIS SILVERFIELD.
